Chavis, Niceville, Fla.

Application March 7, 1950, Serial No. 148,242

10 Claims. (Cl. 200—169)

1

This invention comprises novel and useful improvements in electric alarms, and more particularly pertains to a burglar alarm switch actuating device.

An important object of this invention is to provide a switch actuating mechanism which may be actuated into its closing position by either the application of a pressure directly upon the switch actuating mechanism, or remotely operated by the engagement of a cord by an intruder or the like, which cord is operatively connected to the switch actuating mechanism.

Another object of this invention is to provide a switch actuating mechanism which is particularly adapted to the direct actuation of heavy-duty switches such as are necessary to energize large burglar alarm switches, yet which actuator is extremely sensitive to direct or remotely applied actuating impulses.

A further object of this invention is to provide a switch actuating mechanism which is of compact and simple construction, yet durable and highly efficient for the purposes intended.

An important feature of this invention resides in the provision of a vertically movable switch actuating member, and a brake for releasably retaining the actuating member in its inoperative position.

Another feature of this invention resides in the provision of a vertically movable switch actuating member and a longitudinally movable control member which underlies the actuating member in such a manner that either a downward pressure on the actuating member, or a tensioning of the cord attached to the control member will cause the actuation of the switch actuating member.

Yet another feature of this invention resides in the provision of means for resetting the switch.

These, together with various ancillary objects and features, are attained by this device, a preferred embodiment of which has been illustrated by way of example only in the accompanying drawings, wherein:

Figure 1 is a perspective elevational view of the alarm control unit;

Figure 2 is a horizontal sectional view of the alarm control unit showing a plan view of the switch actuating mechanism;

Figure 3 is a schematic wiring diagram of the circuit in which the alarm unit may be employed;

Figure 4 is a vertical sectional view of the alarm control unit;

Figure 5 is a fragmentary front elevational view showing the means by which the switch

actuating mechanism is connected to the switch;

Figure 6 is a vertical sectional view taken substantially on the plane 6—6 of Figure 2 showing the brake means for the actuating mechanism; and

Figure 7 is a fragmentary sectionalized detail view of the control rod member guide.

Referring now more specifically to the accompanying drawings, wherein like numerals designate similar parts throughout the various views, it can be seen that there is provided an alarm control unit indicated generally by the numeral 10, which unit includes a support or base 12, a standard 14 mounted upon the base 12, and a switch housing 16 mounted upon the standard.

A switch casing 18 is mounted within the housing 16 in any desired manner, and switches 20 and 22 are mounted within the casing 18, a suitable face plate 24 being attached to the casing as by fasteners 26 in order to render the appearance of the unit more efficacious. The switches 20 and 22 are preferably of the single pole, single throw type of switch and each has one of the terminals suitably connected, as by conductors 28 and 30, to a source of power. For this purpose, a conventional receptacle 32 is electrically connected to the conductors 28 and 30, and suitably mounted on the housing 16, as by the strap 34, which receptacle is adapted to receive the plug which is attached to the conductors which lead to the source of power. Each of the other terminals of the switches 20 and 22 are electrically connected as by conductors 34 and 36 to an outlet 38, and also connected as by conductors 40 and 42 to an outlet 44. It is intended that one of the outlets, such as 38, be connected to an alarm circuit in which a conventional bell or buzzer 46 and/or a signal light 48 is connected. It is further intended that the outlet 44 be either connected to another alarm circuit, in which the alarm units are located in a different part of the building or the like, or, alternatively, the outlet 44 may be electrically connected to a similar switch actuating mechanism so that a single light and bell 48 and 46, respectively, may be actuated by any one of a plurality of alarm units.

An actuating member 50 comprising a trapezoidal shaped ring 52 and an actuating rod 54 which is rigidly secured to the trapezoidal ring is vertically movably mounted on the base 12. For this purpose, the actuating rod 54 is extended through a vertical transverse slot 56 in the standard 14, and is terminally pivoted to a bracket 58 which is secured to the base 12. As is believed

readily apparent, the actuating member 50 will pivot about its pivot pin 60 in the bracket 58 and be slidably and guidingly received in the slot 56 in the standard 14. Pivotedly attached to the actuating rod 54, intermediate the ends thereof, and preferably upon that portion which lies within the confines of the hollow standard 14 is a connecting link 62, which connecting link is attached, at its upper end, to the actuating lever of the switch 20 as by wire 64 or the like. It is believed readily apparent that the connecting link could be pivoted to the control handle of the switch 20 without departing from the spirit of this invention. In the event a flexible connector 64 is utilized, it will be necessary to provide a means for resetting the switch, and for this purpose there is provided a lever 66 which is pivoted as by the bracket 68 to the housing 16, one end of which lever is connected as by wire or cord 70 to the control handle for the switch 20. As is believed readily apparent, pivoting of the lever 66 about the bracket 68 will elevate the switch handle to thereby reset the latter.

As it is intended that the weight of the actuating member 50 be sufficient to urge the switch 20 into its alarm circuit energizing position, it is believed obvious that some sort of brake mechanism must be furnished. For this purpose, there is provided a brake bar 72 which is pivoted at one of its ends 14 to the standard 14 so as to lie in substantial vertical alignment with one side of the slot 56. The other end of the brake bar 72 is connected, as by a fastener 76, to a suitable spring 78 which is anchored to the standard 14 as by the fastener 80 in such a manner as to urge the brake bar 72 into engagement with the actuator rod 54. It will thus be seen that there is provided a brake which will impose a yielding resistance to the downward movement of the actuating member 50, irrespective of the position of the actuating rod 54 in the slot 56.

A control bar 82 having a downwardly converging cam surface 84 on its forward end is horizontally movably mounted upon the base 12 by means of a link 86 which is pivotally connected as by the pin 88 to the control rod, and connected as by the pin 90 to an upstanding flange 92 on the base 12. In this manner, a rocking motion of the control bar 82 may be readily accomplished, particularly when the pivot pin 88 is disposed vertically above the pivot pin 90 and the link 86 is in its vertical dead-center position. As the cam portion 84 of the control rod 82 is adapted to underlie the actuating member 50, it is imperative that there be provided some means for limiting pivotal movement of the control rod about the pin 88. For this purpose there is provided a U-shaped guide 94 which overlies the control rod 82 so as to laterally guide the control rod and also limit the aforementioned pivotal movement. An actuating cord 96 is connected to the rear end of the control rod 82, and is adapted to be entrained across passageways through which burglars or the like would generally pass.

The rear portion of the control rod 82 is adapted to overlie the rear portion of the trapezoidal ring 52 and, for reasons which will later become apparent as the following description proceeds, the control rod is suitably recessed, as at 98, so as to form forward and rear vertical abutments 100 and 102, respectively. Obviously, the rear abutment 102 will prevent forward movement of the control rod 82 when the abutment engages the ring 52, the forward abutment 100 limiting rearward movement in a similar manner.

Since, as previously stated, it is desirable to have the forward movement of the control rod 82 limited to that in which the link 86 will lie in a substantially vertical dead-center position, it is intended that at least the rear portion of the ring 52 is deformable so that adjustment of the point of contact between the ring and the rear abutment 102 may be readily accomplished, to produce the aforementioned desideratum.

In operation, the alarm control unit is suitably connected to a source of power by means of the outlet 32, the outlets 38 and 44 being connected either to separate remotely spaced alarm units, or an alarm unit and another alarm control unit. The switch 22 is then manually closed, it being understood that the switch is opened whenever it is desired to de-activate the control units. The control unit 10 can then be set so as to be actuatable solely by a downward pressure upon the actuating member 50, or, alternatively, it may be set so as to be actuatable by either a downward pressure on the control member 50 or by a tensioning of the cord 96.

In the former instance, the brake bar 72 is utilized, the bar serving to hold the actuating rod and members 54 and 50, respectively, in their upper "cocked" position, when the switch 20 and the actuating member 50 are set by a downward movement of the lever 66.

In the second manner of operation, the brake bar 72 is pivoted out of engagement with the actuating rod 54, and locked in that position by a tightening of the fastener 104 which serves as a pivot pin for the brake bar 72, the control rod 82 being moved so that the cam surface 84 underlies the actuating member 50. In this type of setting, a slight downward pressure on the actuating member 50 will obviously cause the control rod 82 to be reciprocated out of its actuating member supporting position, as the latter rides over the cam surface 84 of the control rod. As it is obviously desirable to have a very sensitive control, it is intended that the link 86 be positioned in its vertical dead-center position, as previously discussed. In the event a tension is applied to the cord 96, it is believed apparent that the control rod 82 will also be reciprocated out of its actuating member supporting position, at which time the weight of the actuating member 50 will cause a closing of the switch 20.

From the foregoing, it is thought that the construction and operation of the device will be readily understood, and further discussion is believed to be unnecessary. However, since numerous modifications will readily occur to those skilled in the art after a consideration of the foregoing specification and accompanying drawing, it is not intended to limit the invention to that shown and described, but all suitable modifications may be resorted to falling within the scope of the appended claims.

Having described the invention, what is claimed as new is:

1. A switch actuating mechanism comprising a base, a standard mounted on said base, a housing mounted on said standard, a switch casing mounted in said housing, a switch mounted in said casing, an actuating rod pivotally mounted on said base, an actuating member rigidly secured to said actuating rod, a connecting link pivotally connected to said actuating rod intermediate the ends thereof, means operatively connecting said link to said switch.

2. A switch actuating mechanism comprising a base, a standard mounted on said base, a hous-

ing mounted on said standard, a switch casing mounted in said housing, a switch mounted in said casing, an actuating rod pivotally mounted on said base, an actuating member rigidly secured to said actuating rod, a connecting link pivotally connected to said actuating rod intermediate the ends thereof, means operatively connecting said link to said switch, a resetting lever pivotally mounted on said housing, means operatively connecting said resetting lever to said switch.

3. A switch actuating mechanism comprising a base, a standard mounted on said base, a housing mounted on said standard, a switch casing mounted in said housing, a switch mounted in said casing, an actuating rod pivotally mounted on said base, an actuating member rigidly secured to said actuating rod, a connecting link pivotally connected to said actuating rod intermediate the ends thereof, means operatively connecting said link to said switch, a control bar horizontally movably mounted on said base, a cam portion on said bar, said cam portion underlying said actuating member.

4. A switch actuating mechanism comprising a base, a standard mounted on said base, a housing mounted on said standard, a switch casing mounted in said housing, a switch mounted in said casing, an actuating rod pivotally mounted on said base, an actuating member rigidly secured to said actuating rod, a connecting link pivotally connected to said actuating rod intermediate the ends thereof, means operatively connecting said link to said switch, a control bar horizontally movably mounted on said base, a cam portion on said bar, said cam portion underlying said actuating member, an actuating cord connected to said control bar.

5. A switch actuating mechanism comprising a base, a standard mounted on said base, a housing mounted on said standard, a switch casing mounted in said housing, a switch mounted in said casing, an actuating rod pivotally mounted on said base, an actuating member rigidly secured to said actuating rod, a connecting link pivotally connected to said actuating rod intermediate the ends thereof, means operatively connecting said link to said switch, a brake bar pivoted on said standard, resilient means urging said brake bar into engagement with said actuating rod.

6. A switch actuating mechanism comprising a base, a hollow standard vertically mounted on said base, a housing mounted on said standard, a switch mounted in said housing, said standard having a vertically extending guide slot therein, an actuating rod pivotally mounted on said base and extending through said slot, an actuating member rigidly secured on said rod, a connecting link pivotally connected to said actuating rod within said hollow standard, means operatively connecting said link to said switch.

7. A switch actuating mechanism comprising a base, a hollow standard vertically mounted on said base, a housing mounted on said standard, a switch mounted in said housing, said standard having a vertically extending guide slot therein, an actuating rod pivotally mounted on said base and extending through said slot, an actuating member rigidly secured on said rod, a connecting link pivotally connected to said actuating rod within said hollow standard, means operatively connecting said link to said switch, a link pivotally mounted on said base, a control rod pivotally secured on said link and horizontally mov-

able on said base, a cam face on said bar, said cam face underlying said actuating member.

8. A switch actuating mechanism comprising a base, a hollow standard vertically mounted on said base, a housing mounted on said standard, a switch mounted in said housing, said standard having a vertically extending guide slot therein, an actuating rod pivotally mounted on said base and extending through said slot, an actuating member rigidly secured on said rod, a connecting link pivotally connected to said actuating rod within said hollow standard, means operatively connecting said link to said switch, a link pivotally mounted on said base, a control rod pivotally secured on said link and horizontally movable on said base, a cam face on said control rod, said cam face underlying said actuating member, a portion of said control rod overlying a portion of said actuating member, a pair of spaced abutments on said rod adapted to engage said actuating member to limit lateral movement of said control rod.

9. A switch actuating mechanism comprising a base, a hollow standard vertically mounted on said base, a housing mounted on said standard, a switch mounted in said housing, said standard having a vertically extending guide slot therein, an actuating rod pivotally mounted on said base and extending through said slot, an actuating member rigidly secured on said rod, a connecting link pivotally connected to said actuating rod within said hollow standard, means operatively connecting said link to said switch, a brake bar pivotally mounted on said standard adjacent said slot, resilient means urging said brake bar into engagement with said actuator rod.

10. A switch actuating mechanism comprising a base, a hollow standard vertically mounted on said base, a housing mounted on said standard, a switch mounted in said housing, said standard having a vertically extending guide slot therein, an actuating rod pivotally mounted on said base and extending through said slot, an actuating member rigidly secured on said rod, a connecting link pivotally connected to said actuating rod within said hollow standard, means operatively connecting said link to said switch, a link pivotally mounted on said base, a control rod pivotally secured on said link and horizontally movable on said base, a cam face on said control rod, said cam face underlying said actuating member, a portion of said control rod overlying a portion of said actuating member, a pair of spaced abutments on said control rod adapted to engage said actuating member to limit lateral movement of said control rod, the portion of said actuating member engaged by said abutments being deformable to control the position of said control rod.
